UNITED STATES PATENT OFFICE.

TURNER HUNT NANCE, OF TALLADEGA, ALABAMA.

GIN-SAW GUMMER AND DIE THEREFOR.

SPECIFICATION forming part of Letters Patent No. 374,692, dated December 13, 1887.

Application filed June 18, 1887. Serial No. 241,766. (No model.)

To all whom it may concern:

Be it known that I, TURNER HUNT NANCE, a citizen of the United States, residing at Talladega, in the county of Talladega and State of Alabama, have invented a new and useful Improvement in Gin-Saw Gummers and Pointers, of which the following is a specification.

My invention relates to an improvement in gin-saw gummers and pointers; and it consists in the peculiar construction and combination of devices, that will be more fully set forth hereinafter, and particularly pointed out in the claims.

In the drawings, Figure 1 is an elevation 15 of my gin-saw gummer and pointer, showing the same attached to a gin-saw. Fig. 2 is a top plan view of the same. Fig. 3 is a vertical longitudinal sectional view taken on the line $x-x$ of Fig. 2. Fig. 4 is a transverse sectional view of the same, taken on the line $y-y$ of Fig. 2. Figs. 5, 6, 7, 8, and 9 are detail views showing various forms of the die and punch.

A B represent a pair of metallic bars, which 25 are arranged side by side and constitute the body of the gin-saw gummer and pointer. The inner ends of the said bars are provided with forward-extending ears C. On the inner side of the bar A, near the front end thereof, is 30 made a longitudinal recess, D, in which is located a revoluble die, E, which is provided with a series of radial openings, F, as shown. This die is secured on the inner end of a screw, G, and by means of the said screw the die may 35 be clamped rigidly to the bar in any desired position. H represents a bolt, which extends transversely through the bars A B at a suitable distance from their inner ends, and serves to clamp the said bars together. The head of 40 this bolt projects outward beyond the bar B, and is enlarged, as shown, and the shank of the bolt projects beyond the bar A and passes through a slotted opening made in the lower portion of the vertical arm of a rectangular 45 guide, I. This guide is supported at any desired vertical adjustment by means of a clamping-nut, K, which is screwed onto the threaded extremity of the bolt.

L represents an operating-arm, which is arranged on the upper side of the bar B, and is secured thereto near its outer end by a piv-

otal bolt, M. The inner end of the said operating-arm is provided with an enlarged head, N, in the front side of which is a vertical lateral recess, O.

P represents a clamping-plate, which is secured to the inner side of the head N by means of a set-screw, R. The said clamping-plate is provided at its front end on its inner side with a vertical groove, S, that communicates with 50 the recess in the head.

T represents a punch, which is fitted in the said groove and is arranged in the recess in the head, and is secured in position therein by turning the screw R, so as to clamp the 65 plate P against the punch. A flat spring, U, is secured to the arm L by a set-screw, and the free end of the said spring bears against the inner side of the guide I, and thereby serves to normally move the free end of the rod L 70 laterally from the die, so as to carry the punch from the same.

It will be observed by reference to Fig. 2 that an opening is left between the opposing front sides of the ends of the bars A and B sufficient in width to admit the insertion of one 75 side of the gin-saw.

V represents an operating-lever, which is provided at its outer end with a handle, W. At the inner end of the said lever is formed 80 an eccentric cam, X, which is arranged upon the head of the bolt H, and is pivoted thereon by means of a bolt, Y. This cam is adapted to engage the operating-arm L when the lever is moved inward, to cause the said 85 arm to move the punch toward the die and across the edge of the saw.

Z represents a pair of arms, which have their inner ends pivoted to the outer sides of the ears C. The said arms extend forward and 90 have their outer ends curved upward, as shown, the said upturned ends of the arms being provided with a series of openings, A'.

B' represents a weight, which is provided on its under side with an extended arm, C'. The said arm is arranged between the upturned ends of the arm Z, and is pivoted thereto by means of a bolt, D', which may be inserted through either of the series of openings A'. In the lower side of the arm is made a vertical 95 slot, E', which is adapted to receive the outer edge of the gin-saw, and thereby the said arm 100

constitutes a guide. By reason of the series of openings A' the weight and the guide may be adjusted vertically on the arm Z, and thus adapt the device to be used upon gin-saws of different sizes.

F' represents a gage-arm, which is pivoted to the inner side of one of the arms Z, near the inner end thereof, by means of a set-screw, G'. This set-screw enables the gage-arm to be turned to any desired position and secured therein. At the rear end of the gage-arm is formed a transverse downwardly-extending gage-tooth, H', which is adapted to successively engage the teeth of the gin saw while the machine is being operated.

To the outer side of the bar A, at a suitable distance from the outer end thereof, is pivoted a bell-crank lever, I'.

K' represents a feeding arm, which has one end pivoted to the short arm of the bell-crank lever, and the free end of the said feeding-arm is provided with a transverse tooth, L', adapted to engage the gin-saw teeth successively.

M' represents an arm, which has its rear end secured to the under side of the bar A. The lower front end of the said arm is provided with a longitudinal slot, O', adapted to receive one side of the gin-saw. A handle, P', is provided at its upper end with a threaded stud, which passes through an opening in the rear end of the arm M' and enters the threaded opening in the bar A, and thereby serves to secure the handle and the arm M' rigidly in position under the said bar A.

R' represents a pulley, which is arranged on the under side of the rear end of the bar A and is journaled on a vertical bolt, as shown. A chain, S', of suitable length passes over the said pulley, and has one end attached to the lever V and the other end attached to the bell-crank lever I'.

T' represents a coiled retractile spring which connects the bell-crank lever to the guide I, and serves to normally move the lower end of the said bell-crank lever forward.

U' represents a stop which projects from one side of the operating-arm L and extends toward the operating-lever V. A chain, V', of suitable length connects the operating-lever V and the operating-arm L, and serves to limit the outward movement of the operating-lever.

The operation of my invention is as follows: The arms Z are arranged on the upper side of the gin-saw a and rest upon the usual blocks, b, which separate the said saw from its companions. The rear side of the saw enters the space between the die and the opposing side of the bar B, and the front edge of the saw enters the slot in the guide-arm C. The gage-arm F' is then caused to engage one of the teeth of the gin-saw, and is set at such an angle as will cause it to support the inner end of the body of the machine at such an elevation that the lower end of the opening in the upper side of the die will correspond with the desired depth of the saw-teeth. The feed-arm K' is then caused to engage one of the teeth of

the gin saw, and the arm M' is arranged to receive the rear edge of the saw, the front ends of the said arm bearing against the rear sides of the block b. The punch is then adjusted between the clamp-plate O and the enlarged head of the operating-arm L. The operator then grasps the handle P' with his left hand and grasps the handle W with his right hand and moves the lever V inward, so as to cause the cam at the rear end of the said lever to bear against the outer side of the arm L, so as to force the punch across the edge of the saw and thereby cut out the space between two of the teeth thereof to the required depth. In Fig. 1 of the drawings, c indicates the saw-teeth before being operated upon by the saw set and gummer, and d indicates the teeth that have been operated upon by the same. It will be observed that the V-shaped faces between the saw-teeth do not converge to a sharp point at their inner ends, but are truncated. This is caused by giving a similar shape to the openings in the dies and to the points of the punch. When the lever V is moved outward after each movement of the punch, the chain draws rearward on the bell-crank lever I' against the tension of the spring which connects the said lever to the guide I, and thereby causes the said bell-crank lever to draw rearward upon the feeding-arm K', which feeding-arm, being engaged with one of the saw-teeth, rotates the saw a distance corresponding to the length of one tooth, and thereby presents another tooth to the action of the punch.

In Figs. 5 to 9 I illustrate various forms of the punch and die, which are adapted to be employed in connection with my improved saw gumming and pointing device.

Having thus described my invention, I claim—

1. In a gin saw pointer and gummer, the combination of the main body of the machine, having the arm M' on its under side, adapted to bear against the blocks between the gin-saws, and the arms Z, pivoted to the front end of the main body or portion, and having the weight B' at their outer ends provided with the downward-extending slotted arm C', to balance the machine on the saw, the said arms being adapted to rest upon the upper sides of the blocks between the saws, substantially as described.

2. In a gin-saw pointer and gummer, the combination of the main body of the machine, the arms Z, pivoted to the front end thereof and extending forward therefrom, and the adjustable gage-arm F', pivoted to one of the arms Z and adapted to engage one of the saw-teeth, substantially as described.

3. In a gin-saw pointer and gummer, the combination, with the main body of the machine, of the pivoted arms Z, extending from the front end thereof, for the purpose set forth, and the adjustable gage-arm F', secured to one of the arms Z and adapted to engage one of the saw-teeth, substantially as described.

4. In a gin-saw gummer, the combination

of the body comprising the bars A, B, secured together, one of said bars having the recess D on its inner side, the die in the said recess, the laterally-movable pivoted operating-arm L, 5 provided with the punch, the lever V, pivoted to one side of the body and movable in a horizontal plane, the bell-crank lever I, arranged in a vertical position and pivoted to the opposite side of the body, the feeding-arm K', 10 pivoted to the bell-crank lever and adapted to engage the saw-teeth, the chain V', connecting lever V and arm L, the chain S', connecting the bell-crank lever and said lever V, the guiding-sheave for said chain, the spring U, 15 to force the punch-arm L outward, and the spring T', connected to the bell-crank lever, for the purpose set forth, substantially as described.

5. The combination, in a saw pointer and 20 gummer, of the main portion or body having the recess in its front end to receive one edge of the saw, the die in the said recess on one side of the saw, the laterally-movable operating-arm L, pivoted to the main portion or 25 body and provided with the punch, the lever to move the said arm in one direction and thereby operate the punch, and the spring to move the said arm in the contrary direction and return it to its initial position, substantially as described.

6. The combination, in a saw pointer and 30 gummer, of the bars A, B, having the openings formed between their front ends to admit one edge of the saw, the die arranged in the said 35 opening, the bolt H, connecting the said bars together and having the enlarged head, the operating-lever V, pivoted on the said head and provided with the eccentric-cam at its inner end, the operating-arm L on the upper 40 side of the bar B, and having the punch at its free end, the said bar bearing against the cam, the guide I, secured to the bar A and vertically adjustable thereon, and the spring-bear-

ing between the guide and the arm L, to move the free end of the latter normally from the 45 guide, substantially as described.

7. In a saw pointer and gummer, the operating-arm L, provided with the enlarged head recessed at its front end, the punch arranged in the said recess, the clamping-plate P on 50 one side of the head, and having the groove on the inner side to receive the punch, and the screw R, to secure the clamping-plate in position, in combination with the body on which the arm h is pivoted, having the slot in its 55 front end to receive one edge of the saw, and the die on the side of the said recess opposite the punch, substantially as described.

8. In a saw pointer and gummer, the revolvable die provided with a series of radial openings, substantially as described.

9. In a gin-saw pointer and gummer, the combination of the body, the arm M' on the under side thereof, for the purpose set forth, and the depending handle P', having the 65 threaded upperstem passing through an opening in the arm M' and entering the body, thereby securing one end of the said arm to the said body, substantially as described.

10. The revolvable die provided with a series 70 of radial openings, combined with the reversible punch having its opposite ends pointed, as set forth.

11. The revolvable die provided with a series 75 of radial openings, combined with the punch, and the operating mechanism therefor to cause the punch to work through the radial openings of the die, as set forth.

In testimony that I claim the foregoing as my own I have hereto affixed my signature in 80 presence of two witnesses.

TURNER HUNT NANCE.
